UNITED STATES PATENT OFFICE

1,924,308

CLOSURE CAP

Frederick C. Cruse, Knoxville, Tenn.

Application November 24, 1931
Serial No. 577,066

3 Claims. (Cl. 70—90)

The present invention relates to filling tube closure caps, admirably adapted for use on gasoline tanks and radiators of motor operated vehicles, but whose general application is contemplated by the claims.

It is the chief characteristic of the present invention to provide a novel construction of means whereby the closure cap can be effectively locked on the filling tube, and only removed therefrom by the person in possession of the proper key.

In carrying out my invention I provide the cap with an opening to accommodate a key actuated lock, characterized by lugs adapted to engage cam-like flanges on the interior of the filling tube and opposed stop extensions formed thereon, when the cap is associated with the tube, while the key actuated bolts of the lock when projected cooperate with said stop extensions of the flanges to lock the cap against removal.

The nature and advantages of the invention will be better understood when the following detail description is read in connection with the accompanying drawing, the invention residing in the construction, combination and arrangement of parts as claimed.

In the drawing forming part of this application like numerals of reference indicate similar parts in the several views and wherein:

Figure 1 is a vertical sectional view through the filling tube and cap.

Figure 2 is a horizontal section showing how the cap is locked to the filling tube.

Figure 3 is a similar view showing the locking bolts retracted and the cap positioned to be removed.

Figure 4 is a view similar to Figure 2 with the lug carrying plate of the lock removed.

Figure 5 is a similar view with the locking bolts removed.

Referring to the drawing 10 indicates a filling tube adapted to be closed by the flanged cap 11 provided with the usual gasket 12. The upper edge of the filling tube is turned inwardly to provide opposed depending cam-like flanges 13, each being formed with a stop extension 14 at one end thereof for a purpose to be hereinafter described.

The cap 11 is provided with a central opening to accommodate a key actuated lock, the casing 15 of which is bolted or otherwise suitably secured to the top of the cap. The lower end of the casing is recessed as at 16 and arranged in this recess is a disk 17 secured to the adjacent end of the rotatable member or cylinder 18 of the lock. Also slidably through said recess are the locking bolts 19, each of which is provided

with a transverse groove 20 to receive one of the pins 21 depending from the disk 17. Manifestly the rotation of the member 18 through the instrumentality of the key 22 projects or retracts the bolts 19, depending of course upon the direction of rotation of said member. The disk 17 is notched as at 23 to receive a lug 24 which limits the rotation of the member 18 in either direction.

The bolts 19 are held in the recess by means of a plate 25 bolted or otherwise secured to the adjacent end of the lock casing. Projecting from the edge of the plate 25 at diametrically opposite points are angularly-shaped lugs, each including an upwardly extending portion 26 and a laterally extending portion 27. The corresponding laterally extending portions of these lugs cooperate with both the cam-like flanges of the filling tube and locking bolts to lock the cap on the tube.

In practice, the cap is placed upon the tube with the lugs on the plate 25 passed between the flanges 13, after which the cap is partially rotated to bring said lugs into engagement with the stop extensions 14, the lugs snapping in place. Obviously the lugs contacting the stop extensions 14 of the flanges limit the rotation of the cap in one direction. After the cap has been thus associated with the filling tube, the rotatable member 18 of the lock is turned through the instrumentality of the key 22 to project the bolts 19 outwardly to their active positions. These bolts when projected are located to engage the sides of the extensions 14 opposite the sides of said extensions engaged by the lugs of the plate 25. The key 22 is then removed, and the cap is effectively locked on the tube 10. Manifestly the cap cannot be removed by anyone except the person in possession of the proper key for the rotatable member 18 of the lock. The construction is very simple, and the cap can be quickly and conveniently locked on the filling tube or removed therefrom as the occasion may require, by the person in possession of the proper key.

While it is believed that from the foregoing description the nature and advantages of the invention will be readily apparent, I desire to have it understood that I do not limit myself to what is herein illustrated or described and that such changes may be resorted to when desired as fall within the scope of what is claimed. The type of closure to which this invention is shown applied is disclosed in U. S. Patent No. 1,593,847, issued July 27, 1926, to James S. Reid. In this

patent, the parts 6, 10, 12, 17, 18 and 24, correspond to the parts respectively herein designated at 13, 14, 11, 26, 27 and 12.

What is claimed is:

- 5 1. The combination with a filling tube having spaced internal cam-like flanges provided with depending end stop extensions, of a closure cap having a central opening, a lock having a casing fitted in said central opening of the closure cap, said lock casing having an end flange resting on and secured to the top of said closure cap by means concealed within the latter, said lock including key-actuated bolts arranged to be projected across the lower edges of said cam-like flanges into the path of said stop extensions for locking said closure cap on said filling tube, a plate secured on the bottom of said lock casing for holding said bolts therein, and lugs projecting from the edge of said plate intermediate said bolts and adapted to cooperate with said cam-like flanges for tightly seating the cap on said filling tube.
- 10 2. The combination with a filling tube having spaced internal cam-like flanges provided with depending end stop extensions, of a closure cap, a lock having a casing secured to and depending from said closure cap, a plate secured on the bottom of said lock casing and having angular lugs projecting from its edge to cooperate with said cam-like flanges for tightly seating and holding said cap on said filling tube, said lugs adapted to be positioned between said flanges by turn-

ing of said cap to permit removal of the latter from said filling tube, said lock including key-actuated bolts held in said lock casing by said plate and arranged intermediate said lugs to be projected across the lower edges of said flanges into the path of said stop extensions for preventing the aforesaid turning of the cap and positioning of the lugs and thereby preventing removal of the cap from said filling tube.

3. The combination with a filling tube having spaced internal cam-like flanges provided with depending end stop extensions, of a closure cap, a lock having a casing secured to and depending from said closure cap, a plate secured on the bottom of said lock casing and having lugs projecting from its edge to cooperate with said cam-like flanges for tightly seating and holding said cap on said filling tube, said lugs adapted to be positioned between said flanges by turning of said cap to permit removal of the latter from said filling tube, said lock including key-actuated bolts held in said lock casing by said plate and arranged intermediate said lugs to be projected across the lower edges of said flanges into the path of said stop extensions for preventing the aforesaid turning of the cap and positioning of the lugs and thereby preventing removal of the cap from said filling tube, said cap having a central opening, said lock casing passing through said opening and having a top flange seated and secured on said cap about said opening.
